UNITED STATES PATENT OFFICE

RUDOLF RODERWALD, OF BERLIN, GERMANY, ASSIGNOR TO THE DAYTON RODERWALD COMPANY, OF DAYTON, OHIO, A CORPORATION OF OHIO

DRIVING MECHANISM FOR AXLE-DRIVEN TRAIN LIGHTING DYNAMOS

Application filed October 20, 1930, Serial No. 489,920, and in Germany October 21, 1929.

There is a series of factors which require cushioning of such driving mechanisms against undue strains, especially against shocks due to sudden starting or stopping and to the irregularities of the rails and furthermore against strains or stresses due to the movements of the axle with respect to the truck frame or car.

It is the main object of my invention to absorb an essential part of the said shocks or stresses by an elastic belt, preferably a V-type belt of rubber impregnated cloth and to absorb the resting part of these shocks or stresses by elastic means, especially elastic joints or the like, so that the dynamo is held free from these shocks and the driving mechanism is absorbing successively all stresses, whereby the driving mechanism and the dynamo become adapted to resist to all accidents in the train handling. Therefore it is the object of my invention to employ in combination an elastic belt and an universal joint in the said driving mechanism.

It is a further object of my invention to maintain a constant tension of the belt employed in the said combination irrespective of any fore and aft or lateral movement of the car axle and therefore to employ in combination with the said elastic belt and universal joint a yielding connection, ensuring a constant tension of the said belt and an adjustment of this tension during lateral movements of the axle.

As such a yielding connection I propose to employ a rotatively mounted hanger, the mounting allowing the hanger to swing in a plane parallel to the running plane of the belt, a tension spring ensuring always the proper driving tension.

I furthermore intend to provide means, whereby the driving ratio may be altered in great extent. I obtain this result by employing or inserting in my driving mechanism a plurality of devices the gearing ratio of which may be altered.

For instance the pulleys for the belt may form the first device, gearing wheels, transmitting the force from the driven pulley to the said universal joint may form the second device, beveled gear wheels transmitting

the force from the universal joint to the dynamo may form the third device and if necessary a second pair of pulleys transmitting the force from the driven beveled gear wheel to the dynamo may form the fourth device for altering the gearing ratio.

By my proposal to take the rotational energy from the axle of the car by means of a belt and pulley, I obtain the considerable advantage to do away with gears mounted on the axle, the box of which cannot be held tight, on account of the fact, that it is traversed by this axle.

A further advantage of the V-type belt is to run easier on its pulleys than a wide face belt or unelastic Morse-chain and to automatically adjust the belt position during lateral movements of the car axle.

I also intend to ensure an uninterrupted service with a minimum amount of attention and this result is obtained by providing two belts running parallel to each other, each of which being so dimensioned as to be enabled to take over the total load when the other belt is broken.

A further object of my invention is to facilitate the control of the driving mechanism and to provide means, whereby the belt of the mechanism may be protected against outer adverse influences of all kinds.

Further objects of my invention will arise from the following text, which is a clear description of my said invention.

In the accompanying drawings Fig. 1 is a side view and Fig. 2 a front view of a construction, embodying my invention, Fig. 3 shows in a greater scale a horizontal cross section on the line III—III of Fig. 1, Fig. 4 shows the front view of a detail of the construction illustrated in Fig. 3, Figs. 5 and 6 are respectively a top and a front view of an axle extension-piece, fixed to the end of the axle, the latter being illustrated in Fig. 5 partly in section, Figs. 7 and 8 are similar views as those shown in Figs. 5 and 6 and illustrate a modification, Fig. 9 is a horizontal cross-section similar to that of Fig. 3 showing a modification thereof adapted to provide a box for protecting the belt and pulleys, Fig. 10 is a side view of Fig. 9, Fig. 10

11 a horizontal cross section similar to that of Fig. 3, showing a further modification, Fig. 12 shows an universal joint shaft broken away at both ends, Fig. 13 is a front view of 5 the joint shown in Fig. 12, Figs. 14 and 15 are respectively a sectional and top view of a modification of my invention, the section of Fig. 14 being on line XIV—XIV of Fig. 15, Figs. 16 and 17 are respectively a sectional 10 and a top view of a further modification of my invention, the section of Fig. 16 being on line XVI—XVI of Fig. 17, Fig. 18 is a front view, Fig. 18a is a detail of Fig. 18, Fig. 19 a top view and Fig. 20 a top view of 15 three further modifications, and Fig. 21 a perspective view of a detail of the Fig. 20.

Figs. 22, 23 and 24 show respectively a side, a sectional and a top view of a still further modification, the section of Fig. 23 being 20 on line XXIII—XXIII of Fig. 22. Figs. 25 and 26 show two different modifications of a detail of the embodiment of the Figs. 22—24 in side elevation partly broken away, Fig. 27 shows a side—and Fig. 28 a top—view of a 25 last modification, Fig. 29 shows a side view of a pulley and Fig. 30 a section on line XXX—XXX of Fig. 29.

The mechanical energy for the driving mechanism according to my invention is derived 30 from the axle 1 inside or outside the car-wheels 2. I prefer to derive it outside in order to have better access to the parts for controlling and replacing and in order to be 35 enabled to mount an unsplit driving element on the car axle. In the modification shown in Figs. 1 and 2 I have employed the outside arrangement. The axle 1 is provided with an extension 3. This extension has a middle 40 cylindrical part 4, a conical part 5 and a screw threaded part 6. Integral with the cylindrical part 4 is a disc 7, and integral with the disc 7 is a segment 8 with parallel 45 end walls 9. The axle 1 is provided with a recess 10 to be entered by the said segment 8 and with four screw threaded holes into which screws 11 are screwed in.

The cylindrical part 4 supports the cover 12 of the axle-bearing box and the conical part 5 supports the pulley 13. The oil supply 14 is located inside the cover 12 and the pulley 13 has its periphery likewise retracted to inside, so that the assembly of these parts remains inside the prescribed outline of railway cars. As seen from the drawings 55 relatively simple and compact parts are used in all my constructions.

In the modification of the axle extension illustrated in the Figures 7 and 8, the disc 7¹ is held by four screw bolts 15. Four prison-pins 16 ensure the coincidence of the axis of the axle extension piece with the axis of the axle 1. In this modification the axle 1 is not weakened and the mounting of the extension piece is facilitated.

65 Fixed to the truck frame 17 is a bracket

18 and pivotally mounted therein is a hanger 19. The lower end of the hanger 19 forms the bearing for the shaft 20 of the pulley 21, which is driven by the pulley 13 by a belt 22 and fixed to the hanger 19 or 70 integral therewith is a gearing box 23, containing two gear wheels 24 and 25, meshing with each other. These gear wheels are interchangeable in order to alter the driving ratio. The gear wheel 24 with the greater 75 diameter is fixed to the said shaft 20 and transmits its rotational energy to the gear wheel 25 fixed to the end of an universal joint shaft 26, the other end of which is driving the generator 27, which is adjustably fixed to the truck frame 17.

The said hanger is spring influenced by an adjustable screw spring 28, which tends to normally pull the lower end of the hanger and the pulley 21 in a direction away from 85 the axle 1 and thereby to place the belt 22 under the proper driving tension and to adjust the same when the car is passing curves.

When it is desired to protect the pulleys 13 and 21 and the belt 22 by a box I provide 90 the cover of the axle bearing box with a flange 29 (Fig. 9) adapted to support a box 30 of the form as illustrated in the Figs. 9 and 10. The outlet of the shaft 20 is tightened by two discs 20¹ of coal or the like, 95 travelling with this shaft 20 when swinging in the curved slot 31 around the pivot of the hanger 19.

In the modification shown in Fig. 11 a pulley 32 for two belts is shown. When 100 each of these belts is so dimensioned as to sustain the total load, the security for an uninterrupted service is obtained, when one of the belts is breaking. In order to prevent that the broken belt interferes with the 105 other, tiges 33 or a grate may be provided between the two belts.

The Figs. 12 and 13 show one of the universal joints of the shaft 26 (Fig. 2). Three-armed parts 34 and 35 are so located 110 relatively to each other, that the three arms of the one part lie between the arms of the other part.

Between both parts 34 and 35 a rubber disc 36 is provided and screw bolts 37 inter-connect the rubber disc with the arms. 115

In the modification shown in Figs. 14 and 15 the rotational energy is derived from the axle 1 inside the wheels 2 by a split pulley 13¹ and transmitted by the belt 22 to the 120 pulley 21. Fixed to the sills 38 are bearings 39, in which is fixedly held a shaft 40. Pivotaly mounted thereon is a hanger 19.

The lower end of the hanger 19 forms the bearing 68 for the shaft 20 of the pulley 21, 125 which is driven by the pulley 13¹ by the belt 22 and fixed to the hanger 19 or integral therewith is a gearing box 23, containing two gear wheels with a desired driving ratio. The gear wheel with the greater 130

diameter is fixed to the said shaft 20 and meshes with the gear wheel of the smaller diameter which latter gear wheel is supported within the box by the end of an universal joint shaft 26, the other end of which is driving a bevel gear 41 meshing with a bevel pinion 42. The gear box 43 containing the bevel gear and pinion is held on the one hand by the shaft 40 and on the other hand fixed to the truck frame 17.

The bevel pinion 42 is fixed to a second universal shaft 26¹ driving the generator 27, which is not illustrated in this modification and may be fixed by brackets to the truck frame or to the car. The hanger 19 is spring influenced by an adjustable screw spring 28, in the manner as described above. The said spring 28 tends to normally pull the lower end of the hanger and the pulley 21 in a direction away from the axle 1.

Planetary gears or any other type of gear can be used.

In this modification there are three points at present for inserting a driving ratio, 25 namely the pulleys 13¹ and 21, the gear wheels in the box 23 and the bevel gear wheels in the box 43. If desired the gear ing wheels in the box 23 may be omitted, so that the shaft 20 would rotate the universal 30 joint shaft 26 immediately.

By employing a plurality of points on which the driving ratio may be altered I am enabled to ensure a considerable total driving ratio of say 3:10. Moreover I am 35 enabled to use pulleys of nearly the same diameter for instance 400 mm:300 mm. In this way the great pulley becomes smaller and the small pulley becomes greater.

Therefore it is facilitated to locate the 40 greater pulley whereas the small pulley, the diameter of which becomes greater ensures a longer life of the belt, because the belt is not so sharply bent on a greater pulley.

The modification of the Figures 16 and 45 17 differs from that just described substantially in that the hanger is inverted and the driving ratio of the beveled gear wheels is 1:1.

The rotational energy is derived from the 50 axle 1 by the inside mounted pulley 13¹ which drives by the belt 22 the pulley 21.

Fixed to the truck 17 is a bracket 18¹ and pivotally mounted on the free end of this bracket is an inverted hanger 19¹, the upper 55 end of which supports a bearing box 44 provided with an eye 45. The bearing box 44 supports the shaft 20 of the pulley 21. The said hanger 19¹ is spring influenced by an adjustable screw spring 28, which tends to 60 normally pull the upper end of the hanger and the pulley 21 in a direction away from the axle 1 and thereby to place the belt 22 under the proper driving tension and to adjust the same when the car is passing curves, 65 in the same manner as pointed out above.

The spring 28 considerably assists the belt in its elasticity, with the result that all sudden strains and shocks are elastically absorbed by the belt and hanger. Mounted 70 on and fixed to the free end of the shaft 20 is the one of two gear wheels, meshing with a second gear wheel. Both gear wheels are enclosed in a box 23¹, which is integral with the said bearing box 44.

The said second gear wheel is mounted on 75 an universal joint shaft 26², the other end of which is held in a bracket 46, which is fixed to the truck 17. Fixed to the free end of the universal joint shaft 26² is a bevel gear wheel 47 meshing with a gear wheel 48, which is mounted on and fixed to a shaft 49. This shaft terminates in the coupling of an universal joint shaft 26³, transmitting the force to the dynamo mounted on the car.

The modification of Fig. 18 shows an advantageous mounting of the driving mechanism on passenger-cars with two or three axles. As seen the transmission of the force is the same as described above.

The force is derived inside the wheels 2 from the axle 1 and transmitted by pulley 13¹, belt 22, pulley 21, shaft 20, gear wheels 24, 25 of the box 23 to the universal joint shaft 26 and dynamo 27. In order to support the hanger and the dynamo, a shaft 50 and symmetrically arranged on it a shaft 51 is provided, whereas a further shaft 52 is provided somewhat laterally to the shafts 50 and 51, but in the same level as the shafts 50 and 51 and nearly in the middle between them. The shafts 50 and 51 are held and supported by the main frame 53 and by the sills 54 of the normal frame, whereas the shaft 52 is supported by the sills 54 alone. The shaft 50 forms the pivot for the hanger 19, and on the shaft 51 the dynamo 27 is supported. The shaft 52 supports the holder 55¹ for the adjustable screw spring 28 and supports also a link 55, the under end of which is connected to an eye 56 of the dynamo, so that the latter is rigidly suspended.

In the modification shown in the Fig. 19 the rotational energy is derived outside the wheels 2 from the axle 1 by a bevel gear 57 fixed to the axle 1 and meshing with a gear wheel 58. Both bevel gears are protected by a box 59, which forms the bearing for the one end of an universal joint shaft 26⁴, to which the said bevel gear wheel 58 is fixed to. The other end of the said shaft 26⁴ is supported by a bracket 60. Near to the end of the shaft 26⁴ and fixed thereto between branches of the said bracket is a pulley 13², which drives by a belt 22¹ a pulley 21². The latter is mounted on and fixed to a shaft 61, which is fixed in the free end of a hanger 19. The one end of this shaft 61 enters a box 23 and supports inside this box the greater of two gear wheels. The other end of the said shaft 61 is spring influenced in 125 130

the manner and sense as described above. Supported on a bracket 64 is a bearing 63. Journalled in this bearing 63 and in a bearing not shown mounted on the truck 17 is an universal joint shaft 26, on which the hanger 19 is pivotally mounted and which transmits the rotational energy to a dynamo fixed to the car body. The spring 28 tends to normally pull the pulley 21² in a direction away from the pulley 13² and thereby to place the belt 22¹ under the proper driving tension. In the modification of Fig. 20 the rotational energy is in the same manner as just described derived outside the wheels 2 from the axle 1 by a bevel gear 57 fixed to the axle 1 and transmitted to a bevel gear 58 and universal joint shaft 26⁴. In this modification however the force is transmitted by a second pair of bevel gear wheels 65 and 66. These wheels are lodged in a box 62 supported by a bracket 67 fixed to the truck 17. Supported by the said box 62 are the mentioned shaft 26⁴ and an universal joint shaft 26, the other end of which is journalled in the free end of a hanger 19² and is spring influenced. Between the arms of the hanger 19² a pulley 13³ is fixed to the shaft 26. This pulley drives by a belt 22² a pulley 21³ and the pulley 21³ drives the dynamo 27, which may be fixed to the truck 17 or to the car body as desired. Selfevidently my invention may be incorporated in various other alternative structures. For instance the last described structure can be so modified, that instead of the pulley 13² bevel gear wheels are arranged the smaller driving an universal joint shaft 26⁴, which is so arranged as the shaft 26 in Fig. 19. A further modification would result when instead of the dynamo in Fig. 1 bevel gear wheels were arranged, the smaller gear wheel driving a shaft 26⁴ arranged in the same manner as the shaft 26 in Fig. 19.

The universal joint shaft 26⁴ of Figs. 19 and 20 is made of two parts adapted to be shifted relatively to each other. A prismatical section of the one part and prismatical hollow of the other part prevents rotation of the one part relatively to the other part. A spring 67 ensures the uninterrupted engagement of the bevel gear wheels 57 and 58 during lateral movements of the axle 1.

In the modification shown in Figs. 22-24 the axle bearing box 69 is enlarged by a casing 70 fixedly mounted thereon. Contained in this casing 70 is a casing 71, the latter being provided with openings 72 for the entrance of the oil. Contained in the casing 71 are gear wheels 73 and 74, the gear wheel 73 being mounted on and fixed to an axle extension 3 and the gear wheel 74 being mounted on and fixed to a shaft 75. The

one of the ends of this shaft supports a pulley 13⁴ fixed thereto. Projecting from the inside of the casing 71 is an edge 76. 77 is a tube and 78 a receptacle or recess. Ball bearings are provided on both sides of the wheels 73 and 74. If desired a sieve of metal gauze may be interposed between the parts 69 and 70, the said sieve being adapted to hold the axle and axle bearing cup free from all solid bodies of any kind.

This embodiment has a plurality of special advantages. The oil chamber for the axle bearing box 69 is considerably increased. Oil cannot be lost on account of the high position of the shaft 75. The belt is likewise in a very high position and therefore better protected against snow, flying stones and so forth. The axle 1 is continuously furnished with oil, the latter being lifted by the wheels 73 and 74 and sprayed against the inner surface of the casing 71. It drops from the edge 76 into the recess or receptacle 78 and is guided to the bearing cup and to the axle.

Driven by the pulley 13⁴ by means of a V-type belt is a pulley 21⁴, the shaft 20 of which is beared in the free end of a hanger 19, which is supported by a bracket 19 fixed to the frame 17 and is influenced by a spring 28 and an universal joint shaft 26 drives the dynamo 27 all substantially in the same manner as described above. In this embodiment the spring 28 is free from the weight of the gear box with gearing wheels therein, the latter being located in the casing 71 inside the casing 70. In this place the gear wheels have to transmit a smaller number of revolutions per minute so that their life is prolonged.

In order to lift a sufficient quantity of oil the wheel 73 may be provided with a recess 79 and with channels 80 spraying out the lifted oil as shown in Fig. 25 or wings 81 (Fig. 26) may be provided for the same purpose.

In the modification shown in Figs. 27 and 28 the axle is provided outside the wheels 2 with an axle-extension piece 3 supporting a pulley 82. Between the pulley 82 and a driven pulley 87 further pulleys 84 and 85 with a driving ratio are inserted. The pulley 82 drives by a belt 83 the pulley 84. Fixed thereto is the pulley 85, which drives by a pulley 86 the said pulley 87. The pulleys 84 and 85 are supported by an axis 88, which is beared in the free end of a spring influenced hanger 19. This hanger is journalled on the upper end of an arm 89, which is held in a bearing box 89¹ fixed to the frame 17.

The pulley 87 is fixed to the outer end of an universal joint shaft 26, held by a bracket 90 on the frame 17. The said universal joint shaft 26 drives the dynamo 27.

The pulley 91 shown in Figs. 29 and 30

has openings 92 between the webs 95, so that foreign bodies as for example snow or the like may find an exit through the apertures 94 and 95.

6 In all modifications above described a plurality of elastic transmitting means and a V-type belt of rubber impregnated cloth are employed, the different elastic transmitting means being arranged rectangularly to 10 each other. I obtain in this way a successive absorption of all shocks and strains, the belt absorbing the most part of it and the dynamo remaining free therefrom. Gearing boxes transversed by the car axle are 15 prevented, so that the driving mechanisms according to my invention do not require attention and lubrication, the gear wheels running in closed boxes filled with oil. The V-type belt ensures an exact and correct running even in curves and the combination 20 with the hanger ensures the proper tension under all influences. The plurality of points with a driving ratio ensures a considerable total driving ratio. The arrangement 25 of the several parts of the driving mechanism may be modified as desired, that means that the rotational energy may be derived outside or inside the wheels and that the transmitting means may be located 30 inside or outside of the truck. I prefer to derive the rotational energy outside the wheels in order to have better access to the mechanism and to facilitate the mounting.

Although I have illustrated modifications 35 of this manner, the elastic transmitting means of which being arranged outside the truck, it is clear, that they may also be arranged inside the truck, in combination with the driving belt outside the wheels without 40 leaving the spirit and scope of my invention. The gear wheels being interchangeable, it is possible to meet all requirements with respect to the speed of the dynamo. The latter is rigidly fixed to the truck 45 frame or car body, is however adjustable f. i. by a screw bolt 27¹ (Fig. 2). If desired the spring influenced hanger may be replaced by a spring influenced slide. The employed V-type belt ensures a considerable 50 elasticity and the spring influenced hanger combined with the belt ensures an automatic adjustment of the driving tension during lateral, fore and aft movements of the axle.

This automatic adjustment is facilitated 55 when the gearing box 23 or 23¹ is somewhat displaced from the spring influenced hanger and is located more adjacent to the dynamo 27 instead of being located adjacent to the said hanger.

60 By such displacement the spring 28 is substantially free from the load of the said box and from the weight of the gear wheels contained therein.

Alternative structures differing in the mutual arrangement of the several parts and

in their location inside or outside of the wheels or truck frame are evidently equivalent to the structures described above and I can therefore resort in any event to all such changes, which may be fairly incorporated 70 within the spirit and principle of my above described invention.

What I claim is:

1. In a driving mechanism for axle driven train lighting dynamos the combination of a 75 plurality of elastic transmitting means arranged rectangularly to each other, one of which being formed by a V-type belt of rubber impregnated cloth, a pulley mounted on the end of said axle and engaged by the said belt, a second swinging pulley driven by the said belt and an universal joint shaft rectangularly arranged to the said belt and driven by the driven pulley and a dynamo driven by the said shaft.

2. In a driving mechanism for axle driven train lighting dynamos a pulley on the end of said axle, a belt, a second pulley driven by the said belt, a spring influenced hanger 90 pivotally mounted and supporting the said second pulley and adapted to swing in the direction of the said belt and to adjust thereby the belt tension, a pair of spur gear wheels, the one being driven by the said second pulley and the other driving an universal joint shaft arranged rectangularly to 95 the said belt and a dynamo driven by this shaft.

3. In a driving mechanism for axle driven train lighting dynamos a pulley on the end 100 of said axle, a belt, a second pulley, driven by the said belt, a spring influenced hanger pivotally mounted and supporting the said second pulley and adapted to swing in the direction of the said belt and to adjust thereby the belt tension, an universal joint shaft driven by the said second pulley, the said shaft driving a dynamo and gear wheels between the said second pulley and the said 105 dynamo, the said gear wheels being interchangeable to vary the rotational speed of the said dynamo.

4. In a driving mechanism for axle driven train lighting dynamos a pulley mounted outside the car-wheel on the said axle, a 110 V-type belt, a second pulley driven by the said belt, a spring influenced hanger pivotally mounted and supporting the said second pulley and adapted to swing in the direction of the said belt and to adjust thereby the belt tension, a pair of spur gear wheels, the one being driven by the said second pulley and the other driving an universal joint shaft arranged rectangularly 115 to the said belt and a dynamo driven by this shaft.

5. In a driving mechanism for axle driven train lighting dynamos a pulley mounted outside the car-wheel on an axle-extension-piece, the latter being provided with a disc, 120

the said disc being held by screws on the said axle, a V-type belt, a second pulley driven by the said belt, a spring influenced hanger pivotally mounted and supporting the said second pulley and adapted to swing in the direction of the said belt and to adjust thereby the belt tension, a pair of spur gear wheels, the one being driven by the said second pulley and the other driving an universal joint shaft arranged rectangularly to the said belt and a dynamo driven by this shaft.

6. In a driving mechanism for axle driven train lighting dynamos a pulley on the said axle, a V-type belt, a second pulley driven by the said belt, a spring influenced hanger pivotally mounted and supporting the said second pulley and adapted to swing in the direction of the said belt and to adjust thereby the belt tension, a pair of spur gear wheels, the one being driven by the said second pulley and the other driving an universal joint shaft arranged rectangularly to the said belt and a dynamo driven by this shaft the said universal joint shaft being arranged along and inside the transverse beam of the truck frame of the car, the said hanger being supported on the said beam.

In testimony that I claim the foregoing as my invention, I have signed my name hereto.

RUDOLF RODERWALD.
